UNITED STATES PATENT OFFICE.

FRANK H. BOGDA, OF BURNETT, WISCONSIN.

GATE-LATCH.

1,167,477.

Specification of Letters Patent. Patented Jan. 11, 1916.

Application filed March 20, 1915. Serial No. 15,758.

To all whom it may concern:

Be it known that I, FRANK H. BOGDA, a citizen of the United States, and resident of Burnett, in the county of Dodge and State of Wisconsin, have invented new and useful Improvements in Gate-Latches, of which the following is a description, reference being had to the accompanying drawings, which are a part of this specification.

10 The invention relates to gate latches.

The invention designs more particularly to provide a latch for gates for cattle pens.

15 The invention further designs to provide a gate-latch for a gate which may be swung either inwardly or outwardly and which will automatically lock itself in its intermediate position.

20 The invention further designs to provide a self-locking gate-latch comprising a plurality of locking bolts for engaging the fixed portion of the fence adjacent the gate, and means for simultaneously moving said bolts out of locking engagement to permit opening of the gate in either direction.

25 The invention further designs to provide a new and improved form of gate latch.

30 The invention consists in the several features hereinafter set forth and more particularly defined by claim at the conclusion hereof.

35 In the drawings, Figure 1 is a view of the device embodying the invention, parts being broken away and parts being shown in section; Fig. 2 is a section taken on line 2—2 of Fig. 1; Fig. 3 is a section taken on line 3—3 of Fig. 1.

40 The latch is shown applied to a portion of a gate which is adapted to be swingingly mounted upon one of the fence standards (not shown), and comprises means for locking the gate to another standard 5 of the fence and means for releasing said locking means.

45 The latch comprises a plurality of horizontally extending members 6 which are provided with apertured extensions 7 for receiving a vertically disposed member 8 of the gate. The members 6 are also provided with apertured extensions 9 adjacent one 50 of their ends which are mounted upon a standard 4 of the gate to secure them thereto. The latch further consists of bolts 10 which are slidably mounted in the bores 11 of the members 6, means connected to the standard 5 for receiving the bolts 10, and

means for automatically moving said bolts to locking position.

The means connected to the standard 5 for receiving the bolts 10 comprises channeled members 12 having apertures 13 therein for fitting said members upon the standard 5 and another standard 6' of the fence adjacent thereto. Extensions 14 are provided on one of the ends of the members 12 and each of these extensions has a locking pocket 15 therein and beveled sides 16 and 17 adjacent either side of said pocket. The pockets 15 are adapted to receive the ends 18 of the bolts 10 and the ends of the members 6 extend outwardly to a position adjacent said pockets.

The means for automatically moving each of the bolts 10 to locking position comprises a spring 20 surrounding a reduced portion 21 of the bolt which portion 21 is slidably mounted within an aperture 22 in said member 6, the said spring being interposed between the end of the member 6 and the shouldered portion 23 of said bolt. Each of the springs 20 normally act to move the 80 bolts outwardly so that when the gate is swung in either direction the bolts 10 engaging either the beveled sides 16 or 17 will be moved inwardly against the action of the springs 20, but when they come in line with the pockets 15 the springs 20 will move the bolts outwardly and cause their ends 18 to seat within the pockets. The means for releasing the bolts simultaneously from locking engagement with the pockets comprises 90 linkage operatively connected to said locking bolts 10 and means for simultaneously operating said linkage.

The linkage connected to each of the bolts 10 comprises in each instance a bell crank 95 lever 24 pivotally secured by a pin 25 to a flange 26 on the member 6 and having a hooked end 27 engaging in a horizontally extending vertically disposed slot 28 in the bolt 10, and in a slot 28' in the member 6 100 and have an end 29 pivotally secured to a link 30.

The means for simultaneously operating the linkage above described comprises a grip handle 31 pivotally secured intermediate its 105 bottom portion by a belt 32 to a collar 33 on the standard 4 and to either end of which the ends 34 of the links 30 are pivotally secured.

To release the bolts 10 from locking en- 110

gagement with the pockets 15 all that is necessary is to rotate the handle 31 in either direction which action will cause the links 30 to move inwardly and the hooked ends 27 of the bell crank levers 24 to move inwardly against the locking bolts 10 adjacent the slots 28 and against the action of the springs 20 to move said bolts inwardly and out of the pockets 15.

19 In order that the action of the gate may be self-closing without interference from the bell crank levers 24, I form the slots 28 in the locking bolts of sufficient length to provide a lost motion connection between 15 the bolts 10 and the hooked end 27 of said levers so that the bolts may be moved inwardly when engaging the beveled sides 16 or 17 without interference from said levers.

The operation of the device having been 20 previously described in connection with the description of the parts of the device further detail explanation is deemed unnecessary.

25 The invention thus exemplifies a gate-latch for a gate which may be swung in either direction and automatically locked in mid-position and the locking means of which may be simultaneously released by a single operation.

Copies of this patent may be obtained for five cents each, by addressing the "Commissioner of Patents, Washington, D. C."

The invention is not to be restricted to 30 the details of construction herein set forth, but may be varied so as to be within the scope of the appended claim.

What I claim as my invention is:—

A gate latch comprising horizontally disposed members mounted on the gate and having longitudinally extending bores and slots therein, a pair of locking bolts slidably mounted within said bores and having slots therein, springs disposed within the bores to 40 normally act upon said bolts, locking pocket members on the adjacent fence standard to receive said bolts, and means for unlocking said gate comprising bell-crank levers pivotally connected to said members and having 45 one of their ends slidably mounted in the slots in said members and in the locking bolts, a handle rotatably mounted upon said gate, and links connecting said levers with said handle whereby the handle may be 50 turned in either direction to unlock the gate.

In testimony whereof, I affix my signature, in presence of two witnesses.

FRANK H. BOGDA.
